UNITED STATES PATENT OFFICE.

WALTER SHERRATT, OF TORONTO, ONTARIO, CANADA.

ACID-TANK.

1,125,193.

Specification of Letters Patent. Patented Jan. 19, 1915.

Application filed May 7, 1913. Serial No. 766,171.

To all whom it may concern:

Be it known that I, WALTER SHERRATT, a subject of the King of Great Britain, resident of 62 Dixon avenue, in the city of Toronto, county of York, Province of Ontario, in the Dominion of Canada, engineer, have invented certain new and useful Improvements in Acid-Tanks, of which the following is a specification.

The invention relates to improvements in acid tanks, as described in the present specification and illustrated in the accompanying drawings that form part of the same.

The invention consists essentially in the novel construction and arrangement of parts whereby the parts are securely held together liquid tight without the use of metal pieces in the joints.

The object of the invention is to prolong the life of a tank for containing acid by dispensing with the usual metal accessories such as nails or bolts, which are soon eaten away by the acid and cause leaking and sometimes total collapse of the tank.

In the accompanying drawings Figure 1 is a vertical transverse section. Fig. 2 is a side elevation of a part of the tank length with one corner broken into section. Fig. 3 is a plan view of a portion of the length of the tank and Fig. 4 is an enlarged sectional perspective view of one of the joints.

Like numerals of reference indicate corresponding parts in each figure.

Referring to the drawings 1 is the bottom of the tank comprising a plurality of thick planks each having a tapering tongue 2 at one of its longitudinal edges and a corresponding tapering groove 3 in the opposite longitudinal edge, the tongue of one plank snugly fitting within the groove of the adjacent plank.

In the perpendicular edges at each side respectively of said tongue and said groove, V-shaped recesses 4 are arranged so that the recesses of one plank coincide with the recesses of the adjacent plank when in position, thus leaving a pair of substantially diamond shaped holes between the adjoining edges of said planks one at each side of the tongue and groove and extending the full length of the plank.

In each plank, suitably distanced holes 5 are bored through at intervals from edge to edge substantially central of the thickness and therefore through both the tongue and groove.

When the planks comprising the tank bottom are assembled a length of rubber or other suitable resilient material is placed, in each of the holes formed by V-shaped recesses 4, said lengths extending from end to end of the planks. The assembled planks with the holes 5 coinciding are now placed in a cramp and a wooden tie rod 6 is threaded in said holes right through the bottom from outside edge to outside edge, the ends being split and wedges 7 knocked into said splits. After all of the tie rods 6 have been inserted in this way, which has the effect of compressing the rubber lengths 4^a and thereby making the joint liquid tight, the cramp is taken off, as said planks are just as tightly held together by the tie rods.

The sides 9 and ends 10 are composed of planks held together by the tie rods 11 in exactly the same manner as the bottom 1 the joints 12 being of the same character as the joints in said bottom, the lower planks of said sides and ends each have a depending tongue 8, so that really said tongues form a depending flange all the way around the boundary of the tank, corresponding grooves 13 being cut into the upper surface of the bottom 1 to accommodate said tongues and rubber lengths interposed between the meeting parts of each side tongue and groove in the same manner as that previously described.

Wooden cross pins 14 extend at intervals through corresponding holes in the sides, ends and bottom and through the tie rods of said sides, ends and bottom so that said rods have an additional lock above besides the wedges 7.

As shown in the drawings the sides 9 extend beyond the ends 10 at 15 and, outside of said ends, braces 16 extend across from side to side, holding said sides together by the dove tailed joints 17. It is not thought that any tongue and groove joints are necessary between the vertical side edges of the ends and the adjacent inner face of the sides, but if necessary there may be arranged a joint similar to that between the lower edge of the sides and ends with the bottom 1. However all the corners on the inside of the tank are filled up by the triangular corner pieces 18 secured to the adjacent sides, ends and bottom by wooden dowel pins 19 each of said corner pieces 18 preferably having a V-shaped recess in its right angular corner in which a substantially square sec-

tional length of rubber or other suitable resilient material 20 is inserted and squeezed into the corners of the tank when said pieces are fastened in their places by the dowel pins 19.

It will thus be seen that the whole tank is built up of joined planks throughout without the use of a single metal part, and therefore such a tank will be found extremely 10 serviceable for containing acid for pickling, dyeing and other purposes.

What I claim is:

An acid tank comprising sides, ends and bottom formed respectively of planks joined 15 together with tongue and groove joints, said planks also having longitudinal recesses in their meeting edges, lengths of resilient ma-

terial fitting said recesses and compressed therein, wooden tie bars tying and extending through said sides, ends and bottom 20 from outside edge to outside edge respectively, and a tongue groove joint joining the sides and ends and said bottom, means for joining the ends to the sides and corner pieces fitting in all the inside corners of the 25 tank.

Signed at the city of Toronto, Ontario, Canada, this fifteenth day of February, 1913.

WALTER SHERRATT
